UNITED STATES PATENT OFFICE.

GARTH G. GILPIN, OF RIVERSIDE, ILLINOIS, ASSIGNOR TO WALTER P. MURPHY, OF NEW YORK, N. Y.

REINFORCED DOOR FOR RAILWAY-CARS OF THE DUMPING TYPE.

1,380,055.

Specification of Letters Patent.

Patented May 31, 1921.

Application filed August 30, 1919. Serial No. 320,792.

To all whom it may concern:

Be it known that I, GARTH G. GILPIN, a citizen of the United States, residing at Riverside, in the county of Cook and State 5 of Illinois, have invented certain new and useful Improvements in Reinforced Doors for Railway-Cars of the Dumping Type, of which the following is a specification.

My invention relates to railway cars of 10 the drop bottom or dumping type, and the principal object of the invention is to provide an improved form of sheet metal door for cars of this general type, which will be very strong and rigid. The doors of cars 15 of this character are usually made of sheet metal and have to carry a considerable portion of the load of the cargo. From their mode of operation in opening and closing the doors are subject to additional stresses which 20 tend to deflect and warp them. My invention provides a sheet metal door for general service, hopper or other railway cars of the dumping type, which is reinforced by stiffening ribs or corrugations so as to give 25 the door maximum strength and stiffness to best resist the stresses and pressures to which the door is subjected when in service. The corrugations are so arranged that when the door is used in a car which is constructed 30 so that the load passes over the doors in discharging the corrugations do not hinder the free flow of the material.

The invention consists of the new and improved constructions, arrangements and devices to be hereinafter described and claimed 35 for carrying out the above stated object and such other incidental objects as will appear from the following description of the invention as illustrated in the drawings.

40 In the drawings—

Figure 1 is a fragmentary plan view of a railway car of the general service type furnished with drop bottom panels or doors made in accordance with my invention.

45 Fig. 2 is a vertical sectional view on line 2—2 of Fig. 1, with the door in its open position.

Figs. 3, 4 and 5 are plan views of modified constructions.

50 Like characters of reference designate like parts in the several figures of the drawings.

The door is shown as applied to a general service car but it will be obvious that doors 55 of this character might be used to advantage

in hopper cars or other cars of the dumping type.

Referring first to Figs. 1 and 2, 10 designates one of the side walls of a car, 11 the center sill structure thereof, and 12, 12 the 60 cross members of the under frame. The door consists of a sheet metal panel 13 preferably formed with rigidifying flanges 14 which are down turned and may be pressed out integrally from the body of the sheet 65 to form a continuous rim which gives strength and stiffness to the sheet. The door is hinged to the center sill 11 by means of a pair of hinges 15 comprising, in each case, a member 16 and a strap extension for 70 the same which is angular in cross section so that it tends to give strength and rigidity to the door. With the doors hinged to the car body in this general manner there has been a tendency for the marginal portions 75 of the sheet metal structure outside of the hinge straps to sag and deflect which makes the car leaky. To avoid this, and to give strength and rigidity to the door throughout I preferably press the door sheet so as 80 to form a plurality of diagonally disposed corrugations which will cross the hinge straps and extend close to the lateral edges of the door. In Figs. 1 and 2 I have shown the door sheet as formed with two sets of 85 diagonally disposed corrugations 17 which extend from the hinged and lateral edges of the door toward the center of the door and the edge opposite the hinged edge. This disposition of the corrugations gives very 90 considerable added strength and rigidity to the door structure without materially interfering with the flow of bulk material from the car when the doors are dropped to the position shown in Fig. 2.

95 The corrugations, instead of being disposed as shown in Figs. 1 and 2, might extend from the hinged edge of the door outwardly, as shown at 18, Fig. 3. Or, as shown in Fig. 4, the corrugations, in this figure designated 19, might be parallel to each other and extend diagonally across the sheet. In Fig. 5 I have shown a different arrangement. Here the corrugations 20 radiate from the hinged edge of the door sheet. The disposition of corrugations shown in Figs. 1 and 2 is considered preferable but the other arrangements might be used to advantage to accomplish the desired result, namely, the rigidification of the door, 110

particularly the lateral edges thereof in such a way as to interfere as little as possible with the flow of bulk material over the door.

5 The embodiments illustrated in Figs. 3, 4 and 5 are not claimed specifically herein. The specific features of these embodiments form the subject-matter of my copending divisional application, Serial No. 459,305
10 filed April 7, 1921.

I claim:

1. A sheet metal door for a railway car of the dumping type formed with a plurality of parallel corrugations which extend 15 diagonally across the door in the general direction of movement of the load when discharging.

2. A sheet metal door for a railway car of the dumping type, which door is provided with hinges extending substantially 20 across the door for hinging it to the bottom of the car and is formed with stiffening corrugations which extend diagonally across said hinges, said hinges being secured to the 25 door at points between certain of said corrugations.

3. A sheet metal door for a railway car of the dumping type, which door is provided 30 with hinges extending substantially across the door for hinging it to the bottom of the car and is formed with a plurality of sets of diagonal corrugations which extend one set across each hinge to provide reinforcements to resist longitudinal and lateral deflections of the door.

4. A sheet metal door for a railway car of the dumping type, which door is provided 35 with hinges for hinging it to the bottom of the car and is formed with two sets of diagonally disposed corrugations which extend 40

from the hinged and lateral edges of the door inwardly and toward the edge opposite the hinged edge whereby said corrugations extend substantially in the direction of movement of the load when discharging. 45

5. In a railway car of the dumping car type, the combination with the body of the car, of a sheet metal door, hinges for hinging the door to the body of the car comprising, in each case, a hinge member on the 50 under side of the door and extending substantially across the same, said door being formed with corrugations which extend diagonally across said hinge members in the general direction of the movement of the 55 load when discharging so as to strengthen and rigidify the marginal portions of the door outside of said hinges without substantial interference to the discharge of the load.

6. In a railway car of the dumping car 60 type, the combination with the body of the car, of a sheet metal door, hinges for hinging the door to the body of the car comprising, in each case, a hinge member angular in cross section on the under side of the 65 door and extending across the same, said door being formed with diagonally disposed corrugations which cross said hinge member so as to strengthen and rigidify the marginal portions of the door outside of said hinges. 70

7. In a railway car of the dumping car type, the combination with the body of the car, of a sheet metal door hinged to said car body and formed with a plurality of diagonal corrugations, disposed side by side 75 so as to reinforce substantially the whole area of the door and extending toward the edge of the door opposite the hinged edge.

GARTH G. GILPIN.
